HARRY J. CUDNEY, OF BUFFALO, NEW YORK, ASSIGNOR TO FLEXLUME CORPORATION,
OF TONAWANDA, NEW YORK, A CORPORATION OF NEW YORK

ILLUMINATED SIGN

Application filed July 18, 1928. Serial No. 293,681.

This invention relates to improvements in illuminated signs of the type in which electroluminescent tubes are employed and is particularly directed to the electrical connections between the tubes and the power line.

In the manufacture of such signs, the lengths of the tubes having been ascertained, 10 openings for the terminal portions of the tubes are provided in the sign casing and contact means for the connection of the tubes to power are arranged adjacent such openings. Inasmuch as tubes of any given length cannot be made uniform but always exhibit 15 variations, particularly in the spacing or the angular relation of their angularly extending electrode carrying terminal portions, difficulties have arisen in effecting the connection of such tubes to power and great 20 care must be exercised in securing the certainty and effectiveness of the power connections.

The object of the present invention is a 25 construction and arrangement of parts which will insure effective power connections regardless of variations among the tubes of a given length and without the necessity of any careful or delicate adjustments.

With this object in view the invention contemplates improvements in the form and arrangement of the power line terminal, in the terminal of the tube, and in the co-operative relation of these terminals.

An embodiment of the invention is illustrated in the accompanying drawing, in which:

Figure 1 is a longitudinal sectional view showing my improvement in connection with an insulator assembly.

Figure 2 is a perspective view of the power line terminal.

Figure 3 is an elevation of the inner end of the insulator of said assembly showing 45 the power line terminal in position therein; and

Figure 4 is a plan view of a portion of an electroluminescent tube.

At the outset my invention is to be distinguished from the insulator assembly in

connection with which it is shown, such assembly forming the subject matter of a co-pending joint application for patent Serial No. 293,565 of R. R. Wiley, W. K. Wiley, and myself and being shown in the present 55 case merely as an example of one way of supporting the tube and carrying the power line terminal.

The insulator assembly includes a hollow glass member 1 of general cylindrical form 60 and which has at its inner end an enlargement 2 to provide a chamber for the accommodation of a power line terminal 3.

The terminal 3, which is one of the features of the present invention, may be made in various forms, but is preferably in the form of a strip of resilient metal fashioned to provide a series of adjacent convolutions. As herein shown the strip of metal of which the terminal 3 is composed is bent to provide a 70 number of sinuous convolutions but it may be of any other form suitable for the purposes in view so long as it functions in the manner desired, that is to say to provide a terminal which may be tapped at various 75 points. The power terminal 3 of the form shown is compressed and inserted through the main body portion of the member 1 into the terminal chamber 2. When placed in this chamber the power terminal expands to a length determined by the diameter of the chamber and is thus automatically secured within the member 1. The terminal 3 is connected to the line by a lead-in wire 4 which is preferably passed through an aperture at 80 one side of the member 1 and is connected to the terminal 3 at or near one of its ends.

The end of the member 1 remote from the chamber 2 is flared as indicated at 5 and abuts the inner face of the display wall D of the sign casing against which it is held by a ring 6, which is secured to said wall by bolt and nut fastening 7 and which engages an external shoulder provided by the flare 5. The member 1 is in axial alignment with an opening 8 which is formed in the wall D and through which the electrode carrying terminal portion E of the electroluminescent tube T is introduced, such terminal portion extending from a goose neck bend at the end of 100

the tube in a direction normal to the length of the tube.

5 The insulator assembly is completed by a washer 9 and a bushing 10, these parts being fitted over the terminal carrying portions of the tube before the latter is placed on the sign and functioning to secure the tube to the sign casing.

10 The washer 9 is preferably composed of resilient insulating material. It is formed to fit tightly upon the electrode carrying portion E of the tube and is placed thereon at a point such that when the portion E of the tube is inserted into the member 1 to the extent necessary to connect its terminal 13 to the power terminal 3 the outer marginal edge of the washer has a seating determined by the location of the base of the flared portion 5 of the member 1, a flat gasket 11 being preferably 15 interposed between the washer and said base. The terminal 13 of the tube is in the form of a straight, somewhat elongated, stem or shank with a pointed end to facilitate its entry between the folds or convolutions of the 20 power terminal and is of a diameter which insures its contact with the resilient walls of the adjacent convolutions.

With the parts positioned as above described, the bushing 10 which is loosely fitted 25 on the tube is moved through the wall opening 8 into engagement with the outer marginal edge of the washer 9 to press the latter against its seat. The bushing is preferably formed with threads 12 and the wall of the 30 opening 8 is formed to cooperate with said threads. The outer end of the bushing is flanged to abut the display wall and cooperate with a sealing gasket 14. The insulator 1 is of substantially greater diameter than the 35 electrode carrying portion E and the flared portion 5 of said insulator is of substantially greater diameter than the washer 9. It follows that said insulator will readily accommodate the electrode carrying portions of 40 the tubes of a given length, regardless of variations in the spacing or angular relation of such electrode carrying portions. The tube terminals 13 will also, regardless of variations in the spacing or angular relation of the 45 electrode carrying portions of the tube, effectively engage the power terminals 3 because they will always select and enter some one of the folds of the power terminal and engage the resilient side walls of such fold. 50 The particular fold of the power terminal which may be engaged by the terminal 13 will, of course, depend on the particular position of the electrode carrying portion of the tube in the member 1 and the direction 55 in which said electrode carrying portion may extend. Thus with reference to its position in the member 1 the electrode carrying portion may coincide with the axial center of said member or it may be in varying degree 60 and in either direction off center; and like- 65

wise it may be perpendicular to the tube body or at a slight angle in either direction to the perpendicular, these variations being characteristic of the manufacture of a series of tubes of given length by the glass blowing process which does not admit of precise or exact control of the spacing and angular relation of the electrode carrying portions. 70

It is to be observed that the washer 9 will 75 take a position on its seat which will correspond to the position of the electrode carrying portion of the tube in the member 1 and, being of flexible material, will adapt itself to any slight inclination in the electrode carrying portion relatively to the longitudinal axis of the member 1. 80

While the power terminal 3 may be of any suitable thickness or depth it is preferably 85 made of rather considerable depth and the terminal 13 is likewise made of rather considerable length. These features further insure the effectiveness of the electrical contact of the terminal 13 with the power terminal.

From the foregoing description it will be 90 apparent that the electrical connections constituting the invention greatly facilitate the manufacture of electroluminescent signs and add to the certainty and effectiveness of their operation since, regardless of variations in 95 the spacing and angular relation of the electrode carrying portions of the tube, they provide for effective electric contact between the tube terminal and the power line terminal and in accomplishing this object do not require any laborious or delicate adjustments, the tube terminal being always self-centering with respect to the power line terminal and the electrode carrying portion of the tube always taking any position that may be 100 required within the supporting element. A further advantage is the obvious facility with which the tubes T may be applied to or removed from the sign casing. 105

Having fully described my invention, I 110 claim:

1. In an electric sign, the combination with a wall having an opening, and an electroluminescent tube having an angularly extended electrode carrying terminal portion for insertion through said opening, the latter being of substantially greater diameter than said terminal portion, of a terminal projecting from said terminal portion, and a power line terminal supported behind said opening formed to provide a plurality of tapping points, said terminals being formed for engaging co-operation in any position and angle of said electrode carrying portion with reference to an axis co-inciding with the center of said opening. 115

2. In an electric sign, the combination with a wall having an opening, of a power line terminal supported behind said opening and consisting of a strip of resilient metal fash- 120 125 130

ioned with a series of convolutions, and an electroluminescent tube having an electrode carrying portion for insertion through said opening, and provided with a projecting terminal shank for engagement between adjacent convolutions of said terminal as determined by the position and angle of said electrode carrying portion with reference to an axis coinciding with the center of said opening.

3. In an electric sign, the combination with a wall having an opening, of a power line terminal supported behind said opening and consisting of a strip of resilient metal bent into sinuous form to provide a series of convolutions, and an electroluminescent tube having an electrode carrying portion for insertion through said opening, and provided with a projecting terminal shank for engagement in a fold of said terminal as determined by the position and angle of said electrode carrying portion with reference to an axis coinciding with the center of said opening.

4. In an electric sign, the combination with a wall having an opening, of a power line terminal supported behind said opening and consisting of a strip of resilient metal fashioned with a series of convolutions, said convolutions forming a plurality of sockets accessible through said opening.

5. In an electric sign, the combination with a wall having an opening, of a power line terminal supported behind said opening and consisting of a strip of resilient metal bent into sinuous form to provide a series of convolutions, said convolutions forming a plurality of sockets accessible through said opening.

6. In an electric sign, the combination with a wall having an opening, of a power line terminal supported behind said opening and consisting of a strip of conductive material formed to provide a series of convolutions and an electroluminescent tube having an electrode carrying portion for insertion through said opening and carrying a projecting terminal shank, said shank being pointed to facilitate its entry between adjacent folds of said power terminal.

50 In testimony whereof I hereby affix my signature.

HARRY J. CUDNEY.
